F. E. THOMES

HEATER

Filed March 12, 1927

UNITED STATES PATENT OFFICE.

FRANK E. THOMES, OF SOUTH PORTLAND, MAINE.

HEATER.

Application filed March 12, 1927. Serial No. 174,821.

My invention relates to heating apparatus.

In general terms, my object is to provide a heater having a furnace so constructed and equipped that the lower or cheaper 5 grades of fuel, such as soft or bituminous coal, may be economically used, and which will do away with many of the objectionable features necessarily connected with the operation of the ordinary type of house-hold 10 heater using this particular grade of fuel.

A specific object of my invention is to provide for the proper control and utilization of the gas as it is liberated from the fresh fuel; and another is to prevent the escape of 15 smoke out of the chimney and over the surrounding neighborhood,—this being one of the greatest draw-backs in the use of soft coal in thickly settled communities.

One of the principal objections to feeding 20 soft coal through the ordinary feed-door of the furnace is the belching of smoke and gas into the room. When my heater is properly operated this trouble is largely overcome.

Another object is the provision made 25 whereby the hot-coke portion of the fire-bed may be cleaned and its margins broken down and freed from any upstanding portions which tend to retard the settling or lowering of the fuel from the zone above.

30 And a still further and a principal object of my invention concerns the hot-air and flame flues by means of which communication between the hot-coke zone, situated approximately midway of the depth of the fuel-bed, and the combustion space for gas above the fuel-bed, may be had. The exact 35 function of these flame-flues will hereinafter be fully explained.

Other objects will be apparent from reading 40 the description found in the specification; and in the accompanying drawings in which the preferred embodiment of my invention is illustrated,—

Fig. 1 is a sectional elevation of my heater, 45 shown as a steam generator;

Fig. 2 is the same applied as a hot-air furnace;

Fig. 3 is a fragmentary sectional elevation taken on line 3—3, Fig. 1;

50 Fig. 4 is a fragmentary plan view showing means for oscillating the damper in the heater shown in Fig. 2;

Fig. 5 is a plan view of the grate;

55 Fig. 6 is a fragmentary sectional plan, taken on line 6—6, in Fig. 1;

Fig. 7 is the same taken on line 7—7, Fig. 2, and

Fig. 8 is the same taken on line 8—8, Fig. 2.

Similar parts are represented by the same 60 reference characters in all views of the drawings.

Before describing the structural features of my heater, I will state that I regard the furnace thereof as comprising four vertically arranged, although intangibly divided spaces which I call zones. The lowermost, A is the ash zone, the next above, B, the hot-coke zone, the next C, the space for green or slightly burned fuel and the uppermost, D, 70 the combustion space for gas and smoke.

In Fig. 1, in which my heater is shown as it would function as a steam generator, 1 represents the outer shell and 2 the inner shell and wall of the furnace. These shells 75 inclose an annular space 3 for water and steam.

The base of the furnace may be constructed in any approved manner, but as shown comprises a cylindrical member 4, 80 with provision for an ash door 5.

Suspended on brackets 6, of which there may be three or more attached to the base 4, is a flanged cylindrical member 7, preferably having slots or holes 8 through its vertical 85 wall for the purpose of augmenting the supply of air to the furnace proper.

On a depending frame 9, secured to the member 7, are two grate-bars 10, the openings 11 therein extending substantially 90 across the interior diameter of the member 7. The outer sides of the grate bars have extended portions 12, forming slides which operate in the frame 9 and by means of the shaker-rods 13 the grate-bars may be shaken 95 or withdrawn sufficiently to dump the fire.

Superimposed in close but non-contacting relation to and over the cylindrical member 7 is an annular shaped oscillatory member 14, constituting the bottom of the outlying portions of the furnace. This member is frusto-conical, with the smaller diameter lowermost and terminates at the top with an outwardly disposed flange 15 which is supported on a plurality of ball-bearings 16 105 secured to the base member 4.

On its top surface are radial ribs 17 which act to protect it from the intense heat of the fire in the hot-coke zone by radiating the heat from the plate portion of the member. 110

These ribs also serve as keys which, when the member is oscillated facilitates moving bodily that portion of the fuel-bed which it supports and assists in breaking it from the portion of the fuel-bed directly above.

To operate this inclined furnace bottom member 14 an arm 18, extending outwardly from its under side, is provided, and by means of the pivotally attached rod 19 which passes out through the side of the heater base, the whole bottom outlying portions of the fuel-bed may be agitated, the useless products of combustion, as ashes and clinkers, sliding down the inclined bottom 15 into the ash zone A, from which space they are dislodged by the shaking of the grate.

Located at a considerable distance above the top of the member 14 is the bottom end of the inner shell 2 of the furnace. Through 20 this shell are flue openings 20 offering communication, through the exteriorly disposed flues 21, between the zones B and D,—or in other words, between the hot-coke and the gas burning zones of the furnace.

The fuel level is normally held at a line intermediate the top and bottom ends of the flue openings 20, and as the zone C contains the least burned portion of the fuel-bed the temperature in the furnace at the surface of the fuel is ordinarily much less than it is in zone B which contains always hot-coked material.

Now as the bottom of the flues 21 open directly into the zone B, heat and flame therefrom may pass upwardly through the flues, around zone C into zone D where it consumes the gas and smoke coming off the surface of the fuel-bed.

It is not always required, however, to force 40 the furnace fire to the limit, so I provide a damper which operates to close off the flue openings 20 the proper amount to slacken the fire,—the converse being true when a stronger and more lively fire is required.

45 This damper, 22, is constructed to either rise and fall, as illustrated in the steam boiler type of heater shown in Fig. 1, or to oscillate as is shown in the hot-air heater illustrated in Fig. 2,—the former being actuated by a forked lever 23 and the latter provided with an oblong slot 24 into which a flattened bar (not shown) may be inserted through the feed-door opening 25 and oscillated to open or close the flue openings.

Extending around the upper end of the damper and projecting inwardly is a baffle plate 26. This acts to direct the flame passing up through the flues 21 and deflect it further into the central portion of the combustion chamber over the green fuel.

50 This method of augmenting the facilities for improved ecombustion of the fuel to decrease the smoke nuisance should not be confused with the expedient often resorted to of taking the air from the ash-pit or even from

55 outside the heater through outside flues into the combustion space. The flues 21 in my furnace carry flame and not simply moderately heated air into the zone D, and I am able to regulate the intensity of this flame by 70 the actuation of my flame damper.

The structure illustrated in Fig. 2 contemplates a hot-air heater embodying substantially the same elements as previously described in connection with the form shown 75 in Fig. 1. In the Fig. 2 type of heater I provide removable plates 27 for the reason that this particular portion of the heater is the only one not protected by air on at least one of its exposed surfaces. Heat and flame 80 passing upward through the flues 21 will after a time burn these plates, but they are easily replaced by inserting the upper end in the recess 28 and dropping the lower hooked end 29 over the ledge 30. In Fig. 2 85 I have plotted the direction and course of the flame from zone B into the stack by heavy dotted line L.

The heater shown in Fig. 1 may be provided with steam pipe connection at 31 and return for condensation at 32; also with the usual steam gauge, safety valve, water column and any other necessary auxiliary 90 for operating the boiler,—these fittings not being shown on the drawing. I also provide, in both types of heaters, a clean-out door for 95 zone B, at 33.

In operating my heater the usual procedure in the matter of handling smoke-pipe 100 damper, check draft doors etc. (not shown) is followed. When the fire is to be replenished with soft coal the smoke-pipe damper is opened and the ash-pit door closed. Subsequently, if a strong fire is desired the ash-pit door is opened wide and the flue damper 105 22 adjusted to give the desired amount of auxiliary draft and consequent intensity of flame required.

When a fresh supply of soft coal is fed 110 to the furnace it practically blankets the fire,—or in other words, no great quantity of air can pass through it. One portion of the fuel-bed, however, is less dense and impervious to the air than this fresh fuel portion,—this being the hot-coke zone B. Now 115 as the flues 21 offer direct air communication from the chimney to the zone B, a suction or down-draft on the under side of the fresh fuel takes place and gas freely liberated 120 from this section of the fuel-bed, due to its being in direct contact with the hot zone beneath it, is instantly ignited and passes up the flues in the form of a flame, and as it enters the combustion chamber, or zone D raises this space to a high degree of temperature 125 and shortly effects a liberation of the gas from the upper surface of the fresh fuel,—and we have now a condition where the fuel is being burned on both its upper and under sides with no considerable amount of air 130

passing through its mass. Eventually the whole body of fuel will have become hot coke, but that in zone B will be consumed first, so before replenishing with new fuel, 5 the member 14 should be slightly oscillated,—this movement generally sufficing to bring what remains of the unburned fuel into a compact mass in zone B.

The draft through the flame flues 21 is 10 easily controlled by the damper 22, the adjustment of which will determine the strength and volume of the draft and the consequent intensity of the fire. From the fact that there is always a draft of air pulling 15 through the flame flues when the damper is open, even slightly, it is obvious that the fuel in zone B will be always kept in a condition of glowing heat in contrast to what obtains in the old, conventional type furnace where the blanketing effect of the top body 20 of fuel prevents any appreciable draft passing through the fuel-bed. And as the under side of the body of fuel in zone C is burned more rapidly than the top surface, a larger 25 proportion of gas is liberated and passes downwardly through the hot zone B to enter and pass upwardly through the flues 21 as a flame, intensely heating the walls and surrounding surfaces which radiate this heat to 30 the water or air,—depending on whether steam or hot-air furnaces are involved.

My heater has demonstrated its ability for most economical heating purposes by reason of the fact that a greater than usual proportion 35 of the fuel is completely burned and the heat units more largely conserved and utilized.

Having thus described my invention, what I claim is:

1. A heater comprising in combination, a furnace having a fixed shell portion provided with apertures in the wall thereof, an oscillatory, annular shape bottom member having a downwardly and inwardly inclined upper surface and located in said furnace below and in spaced relation to said fixed shell portion, a plurality of flues located exteriorly of said fixed shell portion and extending upwardly from the space superjacent 45 said oscillatory bottom member to and communicable with the said apertures in said fixed shell portion, a frame disposed beneath said oscillatory bottom member, enclosing a relatively deep chamber, a grate in the bottom end of said chamber, and means to actuate said oscillatory bottom member.

2. A heater comprising in combination, a furnace having a fixed shell portion disposed 50 in the upper portion of said furnace and provided with a plurality of apertures in the wall thereof, an annular plate oscillatively mounted in the lower portion of said furnace, the outer margin thereof extending, 55 horizontally, beyond the wall of said fixed

portion and having its upper surface downwardly and inwardly inclined in spaced relation, vertically, with said fixed shell portion, a plurality of flues located adjacent to and exteriorly of said fixed shell portion and 70 extending downwardly from the apertures in said fixed shell portion into the space superjacent said annular plate, a grate of relatively smaller diameter than the diameter of the said fixed shell portion, and means to 75 vary, either to increase or decrease, the effective openings in the upper ends of said plurality of flues.

3. A heater, comprising in combination, an outer shell, an inner shell having a plurality of apertures in the wall thereof, an oscillatory, annular shape bottom member having a downwardly and inwardly inclined upper surface and located beneath and in vertically spaced relation to said inner shell, 80 a plurality of flues disposed exteriorly of said inner shell, said flues providing communication between the space within said inner shell adjacent the said apertures therein and the space superjacent the said oscillatory bottom member, and an auxiliary damper effective to restrict collectively the areas of the said apertures in the said inner shell. 85

4. A heater, comprising in combination, 90 an outer shell, an inner shell having a plurality of flue apertures in the sides thereof, an oscillatory, annular shape bottom member, its upper surface being downwardly and inwardly inclined and disposed in 100 spaced relation to and beneath the said inner shell, a frame inclosing a relatively deep chamber and being of substantially the same diameter as the inside diameter of said annular bottom member and less than the 105 diameter of said inner shell, a grate disposed within said frame and a plurality of flues disposed exteriorly of said inner shell, each thereof providing communication, above the said grate, between two vertically 110 separated portions of the space within the interior of said heater.

5. A heater, comprising in combination, an outer shell, an inner shell located in the upper portion of said heater and having in its sides a plurality of apertures, an annular, oscillatory bottom member having radial ribs on its upper surface, subtended in spaced relation to said inner shell, a grate operable in spaced relation to said bottom member, a plurality of flues providing independent and separate communication between two vertically spaced portions of the general interior space in said heater, the entrance location to said flues being below said inner shell and the exit location therefrom intermediate the length of said inner shell, both of said locations being above said grate, a perforate cylinder operable adjacent said inner shell and adapted to con- 120 125 130

trol, in conjunction with said flues, a portion of the draft through the fuel space in said heater, whereby said draft may be made ineffectual or may be directed from one portion into another portion of the said fuel space, in various degrees of potency, and a baffle plate inwardly and substantially horizontally disposed on the upper end of said perforate cylinder.

10 6. A heater, comprising in combination, a grate, a furnace, including an inner shell having flue apertures therein, an oscillatory, annular shape member having its upper surface downwardly and inwardly inclined and disposed beneath and in spaced relation to said inner shell, means to actuate said annular shape member, a plurality of flues positioned adjacent said inner shell and provid-

ing communication between two vertically separated portions of the interior of said furnace above said grate, a cylindrical, perforate member adapted to restrict predeterminedly and in various amounts the effective openings in said inner shell, a baffle plate on said cylindrical, perforate member forming an inwardly projecting circumferential flange and adapted to deflect the draft from said flues inwardly toward the central portion of the interior of the furnace, and means to actuate said cylindrical perforate member.

Signed at Portland, in the county of Cumberland and State of Maine, this 21st day of May 1927.

FRANK E. THOMES.
